GAS ANALYZER

Wilfred H. Howe, Sharon, Mass., assignor to The Foxboro Company, Foxboro, Mass., a corporation of Massachusetts

Application August 31, 1954, Serial No. 453,230

9 Claims. (Cl. 23—255)

This invention relates to apparatus for the analysis of mixtures of combustible gases, especially mixtures in such proportions below the lower explosive limit or the upper explosive limit such that combustion in the mixture is not self-sustaining. It particularly relates to electrical bridge apparatus which relies on the familiar principle that induced combustion of such mixtures will occur in a limited area immediately adjacent to a filament which is heated to a temperature above the ignition temperature of the combustible gas. The heat generated by such induced combustion is related to the composition of the mixture, and such apparatus provides a measurement of the heat generated as a measurement of the composition of the mixture under test.

An important use for such apparatus is in chemical operations to measure mixtures of combustible gas and air in order to maintain these mixtures at an optimum composition for the particular chemical operation and still have a safe margin below the lower explosion limit of the mixture.

Conventional apparatus operating on this principle employs a direct current Wheatstone bridge measuring circuit including in one arm a heated filament in contact with the gaseous mixture to be measured. This filament receives heat from two sources. First, a constant direct current potential is applied to the bridge sufficient to maintain a current through the filament which will heat it to a temperature greater than the ignition temperature of the combustible gas, even with no combustible gas present. Second, induced combustion of the gaseous mixture occurring in the area immediately adjacent to the heated filament further heats the filament to an extent related to the composition of the mixture. In this conventional arrangement the Wheatstone bridge measurement of the resistance of the filament thus gives a measure of the composition of the combustible mixture. It is common practice to include a second, duplicate filament in a second arm of the Wheatstone bridge. This duplicate filament resistor is presumably affected by ambient temperature, by minor changes in the supply voltage and by aging effects, exactly the same as the measuring filament is affected so that these conditions do not disturb the relationship between the composition of the gaseous mixture and the resistance readings obtainable from the bridge.

Conventional prior art apparatus of this type employs a platinum filament as a measuring element resistor. This filament deteriorates appreciably when maintained at the necessary temperature just above the ignition temperature for combustible gas. Evaporation and other deterioration of the measuring filament increases exponentially as the temperature of this filament is increased due to the heat from the combustible gas surrounding it. Since the reference filament is not heated by the gas combustion, deterioration of the measuring and reference filaments occurs at different rates, particularly in the measurement of gaseous mixtures approaching the lower explosion limit. This deterioration changes the resist-

2

ance characteristics of the filaments and thus not only upsets the balance of the bridge but also upsets the equality of characteristics between measuring and reference filaments.

5 This difficulty becomes extreme in some gas blending operations where it is important to maintain a mixture at a value as close as possible to the explosion limit while maintaining adequate safety against actual explosive mixtures. In certain processes the yield of useful product increases rapidly as the composition approaches the explosion limit. Since the degree to which the explosion limit can safely be approached is dependent largely upon the accuracy of the measurement and the stability of the control of the composition, it becomes of 15 paramount importance to provide an accurate, stable, reliable measurement. In the conventional constant potential direct current bridge measuring system, the stability and reliability of the measurement falls short of what is desired in spite of frequent extensive and costly maintenance procedures.

20 The present invention overcomes the prior art difficulties by measuring the heat of combustion without the usual temperature rise in the measuring filament and by providing a combination alternating current-direct current bridge circuit arrangement.

25 The present invention provides the concept of a direct current bridge with a measuring resistor filament heated by alternating current, with a control feedback from the output of the bridge to control the alternating current and thereby to control its heating effect, as a means of 30 maintaining a bridge balance condition, and with a direct current function and an alternating current function essentially isolated with respect to each other.

35 Thus the present invention provides a novel gas analyzing system wherein the electrical resistance and hence the temperature of the measuring filament is maintained at a substantially constant value just sufficient to assure induced combustion of the gaseous mixture. This provides for minimum deterioration of the measuring filament. Furthermore, since both the measuring and reference filaments are held at substantially equal resistance, they 40 retain accuracy of balance characteristics over extended periods. This both increases the reliability of the measurement and reduces the maintenance problems in checking and rebalancing the measuring circuit to compensate for rapid deterioration of the measuring filament and also very considerably lengthens the useful life of the measuring filament, thereby reducing the costly replacement and recalibration at frequent intervals required with the conventional system.

45 An embodiment of the present invention, which will be described in detail hereinafter, utilizes a direct current Wheatstone bridge for the measurement of the relative resistance of the measuring and reference filaments in a manner resembling conventional practice. However, current limiting resistance in the direct current supply circuit limits the direct current flow to a relatively small value. In a preferred embodiment the direct current bridge current provides roughly one percent of the total filament heat energy. Separate alternating current heater power circuits are used to supply electrical energy to heat the filaments as a means of providing a constant current supply to the reference filament and a variable current supply to the measurement filament. The current supply to the measurement filament is 50 constantly and automatically controlled so that the heat produced thereby is reduced as the heat of induced combustion of the gas increases, to the end that the measurement filament temperature remains substantially constant. The difference between the electrical heating energy to the measuring element and the electrical heating energy to the reference element is a measure of the thermal 55 60 65 70

heat energy supplied to the measuring element by induced combustion of the gas under test. This difference is thus a measurement of the composition of the measured gaseous mixture. A suitable measuring instrument circuit measures the difference in alternating current supplied to the measuring and reference filaments. This instrument is calibrated directly in terms of composition of the mixture.

A particular feature of this invention is the structure and arrangement by means of which both alternating current and direct current flow is provided in the measuring and reference filaments, with each performing its separate function without appreciable interference with the other. The direct current is prevented from circulating in the alternating current filament heating circuits. The alternating current is substantially blocked out of the direct current bridge supply. Finally, the circuit is designed with an instrument for measuring the direct current balance of the bridge with this instrument substantially unaffected by the alternating current applied to the system. Similarly, an alternating current instrument is provided which measures the relationship between measuring filament current and reference filament current, and thereby the composition of the mixture, with this latter instrument completely independent of the direct current function in the bridge.

It is therefore an object of this invention to provide a new and improved gas analysis device.

Other objects and advantages of this invention will be in part apparent and in part pointed out hereinafter. The objects and advantages of this invention may be appreciated by reference to the accompanying drawing.

The drawing is a schematic illustration of a hot wire gas analyzer system embodying this invention, with the system shown partly in specific electrical circuitry and partly in block diagram showings of standard or common units, power supplies, amplifiers, etc.

The drawing and the following description relate to a specific illustrative embodiment of a hot wire gas analyzer according to this invention. This embodiment is based on an all resistance type of Wheatstone bridge 10 with arms 1, 2, 3, and 4, with arm 3 containing a measuring hot wire resistor filament M at which the gas under test is burned.

The bridge 10 is operated on direct current from a direct current source 11 through leads 12 and 13 to opposing corners 14 and 15 of the bridge, in the usual form of Wheatstone bridge excitation. As will be detailed hereinafter, portions of the bridge, i. e. arms 3 and 4, are also excited by alternating currents for resistor heating purposes. In order for the direct current function of the bridge to be usable, circuit provisions must be made for the compatible operation of the alternating current and direct current systems. These provisions include, in the direct current bridge leads 12 and 13 from the direct current source 11, 500 ohm fixed resistors (16) (17). The direct current source is floating with respect to ground in order not to interfere with the operation of the bridge, which is grounded at a specific point 18, namely, at the junction of the bridge arms 3 and 4.

About 100 volts are applied by the direct current source to the two 500 ohm fixed resistors 16 and 17 in the bridge leads 12 and 13, and the bridge is thus supplied with about 100 ma. of direct current. The alternating current in the bridge is supplied at 12 volts and 1000 cycles and at about one ampere of heating current, so that the 100 ma. of direct current has no appreciable effect on the alternating current function. As a further provision for making the alternating current and direct current operations compatible, the bridge arms 1 and 2 are provided with 500 ohm fixed resistors 19 and 20, and the unbalance output of the bridge is taken from the junction point 21 of the bridge arms 1 and 2. Thus

the direct current function of the bridge is not undesirably affected by the alternating current in the bridge.

In the bridge 10, arm 3 is the measurement arm, and is made up of a series arrangement of two one ohm resistors, M and m with resistor m adjacent the bridge ground point 18, and resistor M adjacent the bridge arm 2. These low value resistors provide a path of low impedance to the alternating current, and also facilitate the measurement of current in these resistors as a factor in the operation of the gas analyzer. The resistor M is the measuring hot wire resistor at which the gas under test is burned. This measuring resistor M is selected to have a high coefficient with respect to temperature, using platinum for example, in order to provide good response in the form of tendency to resistance change and consequent bridge unbalance when the heat of combustion of the gas under test is applied to the resistor M. Further, the measuring resistor M is indicated as being contained in a combustion chamber 22 which is so arranged that a gas sample can be continuously drawn or pushed through it.

The resistor m is a standard resistor selected to have a low coefficient with respect to temperature, in order to provide, for current measurement purposes, an unchanging vehicle for the alternating current changes which occur in the measuring resistor M, as will be seen hereinafter, as a result of the application thereto of the heat of combustion of the gas under test.

Thus, gas combustion heat results in changes in the alternating current values in the measuring resistor M, while measurement of such current values may be made in the adjacent unchanging standard resistor m.

The bridge arm 4 is a duplicate of the bridge arm 3. Two one ohm resistors R and r are arranged in series in this arm. The resistor R is used as a reference resistor; it is adjacent the bridge arm 1; and it is contained in a chamber 23 which is sealed, but otherwise is comparable to the combustion chamber 22 of the measuring resistor M.

These chambers, 22 and 23, may be connected by a passage (not shown) so that the same atmosphere of burned gas may surround both the measuring resistor M and the reference resistor R. In this fashion the temperatures of resistors M and R may be closely controlled with respect to each other since thermal conductivity is the same in each of the resistor ambiances. In such an arrangement the heat of gas combustion which is applied to the reference resistor R is negligible.

The resistor r, as the second resistor in the series of the bridge arm 4, is a standard resistor, like the resistor m of the bridge arm 3, and the resistor r is adjacent the bridge ground point 18.

The bridge arms 3 and 4 are provided with 1000 cycle alternating current for the purpose of heating the measuring and reference resistors M and R. The alternating current in the reference resistor R is provided as a fixed component, while the alternating current in the measuring resistor M is provided as a controllable, variable component.

The source of the alternating current which is applied to the bridge 10 is indicated at the right of the drawing at 24, in block outline form. This source may be used to provide all the alternating current in the whole analyzer system, as a means of tying all the circuits together to prevent inaccuracies due to supply variations. For example, the frequency and phasing of alternating currents from different sources may vary undesirably, reducing the accuracy of the gas analyzer. Further, variations in hot wire resistance due to fluctuations in heating current are cancelled by similarly applying heating current to the reference resistance. Consequently, the effect of such fluctuations on the output of the bridge is negligible.

The 1000 cycle alternating current source 24 is an oscillator which, through leads 25 and 26, provides

activating alternating current to a distribution transformer 27. From the distribution transformer 27, leads 28 and 29 carry the alternating current to the bridge 10, by way of a pair of amplifiers 30 and 31. These amplifiers are powered from a common power supply 32. The gain of the amplifier 30 is fixed, and its output is applied across the bridge arm 4 through a transformer 33. The secondary of the transformer 33 is part of a circuit which includes the bridge arm 4 and consequently the reference resistor R and the standard resistor r. As a part of this reference resistor circuit a connection from the bridge ground point 18 to the secondary of the transformer contains a direct current blocking condenser 34 and an associated choke 35 for relating the alternating current to the condenser 34.

The variable gain amplifier 31 applies alternating current across the bridge arm 3, and therefore to the measuring resistor M and its associated standard resistor m, through a transformer 36. The measuring resistor bridge arm 3 is part of an alternating current circuit including the secondary of the transformer 36 and a blocking condenser 37 with an associated choke 38, in manner and purpose comparable to the alternating current circuit of the reference resistor r.

The pattern of alternating current-direct current operation compatibility in the bridge 10 is thus complete. Undesirable alternating current effects are kept from the direct current input by the 500 ohm resistors 16 and 17, and from the direct current output by the 500 ohm resistors 19 and 20 in the bridge arms 1 and 2. In the alternating current section of the bridge, the direct current component is confined to the bridge and kept from leaking off into alternating current circuits, by the blocking condensers 34 and 37 in the alternating current circuits which include the bridge arms 4 and 3 respectively.

The alternating current components as supplied to the bridge 10 are also compatible with each other, that is, they are essentially isolated from each other, since the transformer secondary circuits provide complete, low impedance circuits which are essentially independent of each other.

In view of the foregoing, therefore, the reference resistor R may be considered to be initially heated to a predetermined temperature by the alternating current component therein. The resistor R is heated, for practical purposes, only by the alternating current therein. The application of the output of the fixed gain amplifier 30 to the bridge arm 4 presumably provides a fixed value alternating current in the reference resistor R, with the result that the resistor R is presumably heated to a predetermined fixed temperature and is presumably provided with a predetermined, fixed resistance value. While the standard resistor r is subjected to the same alternating current, its coefficient with respect to temperature is low and its temperature and resistance values remain essentially unchanged.

The variable gain amplifier 31 is initially adjusted in its application of alternating current to the bridge arm 3 until the bridge 10 is balanced, usually because the measuring resistor M is provided with a resistance value which is balanced against the resistance value of the reference resistor R, as heated by alternating current from the fixed gain amplifier 30.

Thus the bridge 10 is in condition for operation. It is excited with direct current, portions 3 and 4 of it are heated by alternating current, and the bridge is balanced both with respect to direct current and with respect to alternating current.

At this point a gas sample is introduced into the measuring resistor combustion chamber 22 and the heated measuring resistor M at least initiates combustion in the gas sample. The measuring resistor M may be specially treated to provide catalytic combustion of the gas; the gas combustion may be due mainly to the

heat from the resistor M; the combustion may result in part from the heat of combustion itself; or there may be a combination of these factors which result in the burning of the gas sample. At any rate, the bridge 10 is balanced before the gas combustion, and heat of combustion of the gas tends to create a bridge unbalance condition, since the application of heat of combustion to the measuring resistor M tends to change its resistance value. The resultant bridge tendency to unbalance is a factor in the measurement of the degree of combustibility of the gas under test.

The output from the bridge 10 is the voltage drop from the bridge output point 21 to ground, that is, to the bridge ground point 18. This output is applied through a lead 39 and an alternating current filter 40 to a unit 40' which is a direct current voltage detector and amplifier. The output of the unit 40' is applied to the variable gain amplifier 31 as a control feedback which varies the alternating current in the bridge arm 3 in accordance with the bridge unbalance condition.

The operation of the bridge 10, therefore, may be summarized as follows: The bridge is activated by direct current, and the reference and measuring resistors R and M are initially heated by alternating current in such a manner that the bridge is balanced. A sample of the gas under test is exposed to the heated measuring resistor M, and the gas sample is burned. The heat of combustion of the gas is applied to the measuring resistor M with the result that the resistance value of the measuring resistor M is increased. This increased resistance unbalances the bridge and through the detector and amplifier unit 40', brings the control feedback into operation to reduce the gain of the variable gain amplifier 31, with the result that the alternating current in the measuring resistor M is reduced. Consequently the heating effect of the alternating current is reduced and the resistance value of the measuring resistor M is reduced to its initial value, and the bridge 10 is rebalanced.

The effect of the above action on the measuring resistor M is to substitute heat from the gas combustion for heat from the alternating current, with the resulting current reduction available as a factor in the measurement of the degree of combustibility of the gas under test. In the operation of the bridge 10, therefore, the temperatures and resistance values of the reference and measuring resistors R and M are maintained essentially equal, with the variant being the alternating current value in the measuring resistor M.

Various conditions in the bridge are representative of the amount of heat applied to the measuring resistor M as a result of the combustion of the gas under test. The tendency toward bridge unbalance is one such condition, and the resultant change in the heating alternating current in the measuring resistor is another. However, the factor which is used as a measurable condition in representation of the degree of combustibility of the gas under test, i. e. in representation of the heat of combustion of the gas under test, is the ratio between the alternating current in the reference resistor R and the alternating current in the measuring resistor M. For practical purposes these same current values exist respectively in the reference standard resistor r and in the measuring standard resistor m. The only effective variant in these standard resistors is alternating current, and these resistors r and m are used in a pseudo bridge potentiometric measuring circuit 38. The reference and measuring resistors R and M are not included in this measuring circuit.

The pseudo bridge circuit comprises the standard resistors r and m as two adjacent bridge arms with the ground point 18 therebetween, a pair of 100,000 ohm resistors connected to the midpoints of the measuring and reference bridge arms 3 and 4, between the standard resistor and the measuring or reference resistor as the case may be, and a 50,000 ohm resistor connecting the outer ends of the two 100,000 ohm resistors. A connec-

tion slider 41 is provided on the 50,000 ohm resistor in the mid-point area thereof, with an output lead 42 extending from the connection slider 41.

The pseudo bridge 38 is not a true bridge because there is no appreciable variation of any of the resistor values. Instead, the current values are made to differ in different arms of this bridge, and the ratio between these currents is measured in potentiometric fashion. The potentials at the connections between the standard resistors r and m and their respectively associated reference and measuring resistors R and M are a measure of the 1000 cycle current values in the reference and measuring resistors. Further, the potential on the slider connection 41 is a measure of the difference in potential across the standard resistors r and m . Since this slider connection "difference" voltage is proportional to the ratio between the current in the reference standard resistor r and the current in the measuring standard resistor m , the slider connection (41) potential is a measure of the unbalance between the measuring and the reference resistors M and R , and of the degree of combustibility of the gas under test.

The potential at the slider connection 41 is used to provide a record of the degree of combustibility of the gas under test, by applying this potential to a recording system which is shown in the drawing as enclosed in a dotted line box 43.

The lead 42 from the slider connection 41 to the recording system 43 is provided with a blocking condenser 44 to prevent any direct current from reaching the recording system, and a 1000 cycle tuned filter 45 is provided between the lead 42 and ground. This filter has an impedance to 1000 cycle alternating current in the order of one-half megohm, with very much lower impedance to all other frequencies. As a result, the filter forms an effective by-pass to spurious "noise" frequencies. A variable coupling condenser 46 is located in the slider connection lead 42 beyond the tuned filter 45, as an impedance for controlling the effectiveness of the hot wire bridge (10) output voltage, and the sensitivity of the recording system 43.

The recording system 43 may be considered as a servo amplifier with a balanceable recorder bridge 47 therein. The output of the recorder bridge 47, from the bridge unbalance point 48, is connected to the pseudo-bridge output lead 42, with the resultant voltage fed through an unbalance voltage amplifier 49 to the rest of the rebalancing servo network.

The remainder of the servo network comprises an unbalance voltage detector 50, a power amplifier 51 and a pen drive motor 52, with the pen drive motor producing a mechanical movement. A mechanical connection 53 is used to apply the pen drive movement to adjust a variable, rebalancing condenser 54 in the recorder bridge 47. This condenser adjustment movement is applied, through a mechanical connection 55, to a recorder pen 56 as a means of moving the pen 56 generally radially over a rotating chart 57.

The recorder bridge 47 is formed with the upper arms thereof each having a variable condenser therein, one of which is the previously mentioned rebalancing condenser 54; and with the lower arms thereof each provided with a fixed resistor 58, 59. The output connection 48 of the recorder bridge 47 is between the two variable condensers, and the ground connection 60 of the recorder bridge 47 is between the two fixed resistors 58, 59. The recorder bridge 47 is excited from the distribution transformer 27, and the servo network is provided with 1000 cycle alternating current from the oscillator 24 through leads 61, 62 to the unbalance voltage detector 50.

The gas analyzer described herein therefore operates to supply heating, alternating current of a suitable fixed value to the reference resistor R , and heating, alternating current of a variable value to the measuring resistor M .

This current to the measuring resistor M is controlled at a value such that the resistance, and hence, presumably, the temperature of the measuring resistor M , is the same as that of the reference resistor R . The recording system 43 provides a continuous record of the relation of the alternating currents in the reference and measuring resistors R and M . The difference between these currents is presumably due to the heat supplied to the measuring resistor R by the combustion of the gas under test, and hence the record shows the approach to the explosive limit of the gas. The analyzer depends on a combined direct current and 1000 cycle alternating current operation of the hot wire bridge 10 and its associated structure. The direct current bridge 10 circuit measures the resistance of the reference and measuring resistors R and M . Unbalance of this bridge 10, operating through the direct current amplifier 40', provides a direct current control to the 1000 cycle variable gain amplifier 31 and consequently to the alternating current in the measuring resistor M . This control operates on the alternating current supply from the variable gain amplifier 31 to hold this supply to such a value that the resistance of the measuring resistor M is maintained equal to the resistance of the reference resistor R , which is heated by the constant 1000 cycle alternating current supply from the fixed gain amplifier 30. A continuous record of the ratio of the two alternating current heating currents in the measuring and reference resistors M and R in effect represents the reduced electrical heating of the measuring resistor M as its heating current is reduced, and thereby, the amount of heat supplied by combustion of the gas sample.

This invention therefore provides a new and improved gas analysis device of the hot wire type.

As many embodiments may be made of the above invention, and as changes may be made in the embodiments set forth above, without departing from the scope of the invention, it is to be understood that all matter hereinbefore set forth or shown in the accompanying drawing is to be interpreted as illustrative only and not in a limiting sense.

I claim:

1. In an electrical bridge gas combustibility measuring system, in combination, a direct current excited electrical bridge, a reference resistance in one arm of said bridge, a measuring resistance in another arm of said bridge, means for associating gas with said measuring resistance for combustion by heat from said measuring resistance, a first alternating current supply means essentially exclusively operatively associated with said reference resistance arm for producing a predetermined set value of alternating current in said reference resistance, a second alternating current supply means essentially exclusively operatively associated with said measuring resistance arm for producing and varying a gas combustion temperature in said measuring resistance, means operatively connecting the output of said direct current bridge to said second alternating current supply means, whereby a predetermined resistance value relation is maintained between said measuring resistance and said reference resistance, and means for making the direct current function in said bridge compatible with respect to said alternating current components.

2. A hot wire electrical bridge circuit gas analyzer comprising, in combination, a direct current excited bridge, a reference resistor and a measuring resistor in different portions of said bridge, means for heating said reference resistor by applying a fixed alternating current essentially exclusively to said reference resistor portion of said bridge, means for heating said measuring resistor by applying a variable alternating current essentially exclusively to said measuring resistor portion of said bridge, means for burning a gas adjacent said measuring resistor to tend to change the balance condition of said bridge by tending to change the resistance value of

said measuring resistor, and means for varying said variable alternating current to change the heating effect thereof in accordance with unbalance conditions of said bridge and in representation of the degree of combustibility of said gas, said means for varying said variable alternating current including an electrical connection from the output of said bridge to said variable alternating current applying means.

3. A hot wire electrical gas analyzer wherein the temperature of the measuring hot wire results from the additive effect of the heat generated by electric current flow in the hot wire and from heat from induced combustion of the measured gas, said temperature being maintained substantially constant by automatically increasing or decreasing the electrical heating current as the heat of combustion of the gas decreases or increases, comprising in combination, a direct current system with a bridge circuit including in adjacent arms a reference hot wire and a measuring hot wire, a source of substantially constant alternating current connected to electrically heat said reference hot wire, a source of variable alternating current connected to electrically heat said measuring hot wire, a control circuit for controlling the magnitude of said variable alternating current, a connection from the output of said direct current bridge to operatively affect said control circuit, said direct current bridge, said control circuit and said alternating current sources providing a feedback-control loop, whereby the condition of balance of said direct current bridge and the relative resistances of the measuring and reference hot wires are maintained substantially constant thereby maintaining said measuring hot wire at a substantially constant predetermined temperature sufficient to assure combustion of the measured gas, circuit provisions for the compatible operation of the functions of said alternating and direct currents, including predetermined and sufficient alternating current impedance in the direct current power supply, the balancing arms of the direct current bridge, and the direct current input to the control circuit, to limit the alternating current flow in these circuit elements, and predetermined and sufficient direct current impedance in the fixed and variable alternating current sources and in the alternating current comparison circuit to limit the direct current therein, means for comparing the variable alternating current in said measuring hot wire and the substantially fixed alternating current in said reference hot wire, and means operable from said comparison of the variable and substantially fixed alternating currents to provide a measurement of the heat of combustion and hence of the composition of the measured gas for the operation of indicating, recording and control means singly and in any combination thereof.

4. A hot wire electrical gas analyzer comprising, a Wheatstone bridge, a direct current source connected to energize said bridge, a reference resistor in one arm of said bridge, a measuring resistor in another arm of said bridge for receiving heat of combustion of a gas as a means of determining the degree of combustibility of said gas, a controlled alternating current supply network arranged to provide constant heating excitation essentially exclusively to said reference resistor arm and to provide variable heating excitation essentially exclusively to said measuring resistor arm, a feedback connection from the output of the direct current bridge to the controlled alternating current supply to provide a control of alternating current supply to the measuring resistor as a means of automatically maintaining direct current bridge balance and consequently essential equality of resistances in the measuring and reference resistors, and means for essentially isolating the direct current function in said bridge with respect to said alternating current component whereby change in said controlled alternating current is available as a gas combustibility measurement signal for the operation of recording, indicating and control means, singly and in any combination thereof.

5. In a hot wire electrical bridge circuit gas analyzer, wherein a gas is burned at the hot wire with the result that the heat of such combustion tends to change the electrical resistance of the hot wire to produce a bridge balance condition changing effect which is a measure of the degree of combustibility of the gas under test, in combination, a direct current operated bridge for measuring resistance change in said bridge, a measuring hot wire resistor heated by a variable alternating current, a control feedback from the output of said bridge to said variable alternating current, means for essentially isolating the direct current function in said bridge circuit with respect to said variable alternating current, and an alternating current pseudo bridge including an alternating current portion of said direct current bridge for potentiometrically measuring alternating current change in said bridge.

6. In a gas analyzer wherein the electrical condition of a balanceable electrical bridge is influenced by heat of combustion of a sample of the gas under test in representation of the degree of combustibility of the gas under test; a direct current excited and balanceable bridge, a reference resistor in one arm of said bridge, a measuring resistor in another arm of said bridge for responsive association with said heat of combustion of said gas sample, means for applying a fixed value alternating current effectively exclusively to said reference resistor bridge arm as a heating action to establish a resistance value in said reference resistor, means for applying a variable value alternating current effectively exclusively to said measuring resistor bridge arm as a heating action to establish a resistance value in said measuring resistor as a balancing action with respect to said reference resistor, control feedback means from the output of said bridge for varying said variable alternating current with direct current in accordance with unbalance conditions of said bridge, whereby a tendency to change the balance condition of said bridge is automatically counteracted by a change in said variable alternating current as representative of the degree of combustibility of the gas under test and with a consequent change in the resistance value producing heating effect of the variable alternating current, whereby said variable alternating current change is available as a gas combustibility measurement signal for the operation of recording, indicating, and control means, singly and in any combination thereof.

7. A hot wire electrical bridge circuit gas analyzer, wherein a gas is burned by catalytic combustion at the hot wire with the result that the heat of such combustion tends to change the electrical resistance of the hot wire to produce a bridge balance condition changing effect which is a measure of the degree of combustibility of the gas under test, comprising, in combination, a direct current operated bridge, a measuring hot wire resistor and a standard resistor in series therewith in one arm of said bridge, with said arm heated by variable alternating current, a control feedback from the output of said bridge to said variable alternating current, means for essentially isolating the direct current function in said bridge circuit with respect to said variable alternating current, and a pseudo bridge for potentiometrically measuring changes in the alternating current in said measuring resistor arm, said pseudo bridge including said standard resistor and excluding said measuring resistor.

8. In an electrical bridge gas combustibility measuring system, in combination, a direct current excited electrical bridge, a reference resistance and a standard resistance in series therewith in one arm of said bridge, high temperature coefficient measuring resistance and a low temperature coefficient standard resistance in series therewith in another arm of said bridge in opposition to said reference resistance arm, means for associating gas with said measuring resistance for burning by catalytic combustion at said measuring resistance, a first alternating current supply means for essentially exclusively heating said ref-

11

erence arm and producing a predetermined set value in said reference resistance, a second alternating current supply means for essentially exclusively heating said measuring arm and for producing and varying a gas combustion temperature in said measuring resistance, means operatively connecting the output of said direct current bridge to said second alternating current supply means, whereby a predetermined resistance value relation is maintained between said measuring resistance and said reference resistance, means for essentially isolating the direct current function in said bridge with respect to said alternating current components, and a pseudo bridge for potentiometrically measuring the ratio between alternating current in said measuring resistance arm and alternating current in said reference resistance arm, said pseudo bridge including said standard resistances.

9. A hot wire electrical bridge circuit gas analyzer, wherein gas is burned by catalytic combustion at the hot wire with the result that the heat of such combustion tends to change the electrical resistance of the hot wire to produce a bridge balance condition changing effect which is a measure of the degree of combustibility of the gas under test, comprising, in combination, a Wheatstone bridge, said bridge having a 500 ohm resistor in each of two adjacent arms, a one ohm reference resistor and a one ohm standard resistor in series in a third arm of said bridge and a one ohm high temperature coefficient measuring resistor and a one ohm low temperature coefficient standard resistor in series in the fourth arm of said bridge, a 100 volt direct current supply having 500 ohm resistance leads to said bridge between each of said

12

5 500 ohm arms and their respectively adjacent one ohm resistor arms, said bridge having a ground connection between said one ohm resistor arms and an output connection between said 500 ohm arms, a gas sample combustion chamber containing said measuring resistor, a controlled 1000 cycle, 12 volt, alternating current supply network arranged to provide constant heating excitation to said reference resistor arm and to provide variable heating excitation to said measuring resistor arm, a direct current blocking condenser arrangement between said bridge and said alternating current supply network, a control feedback connection from the output of the direct current bridge to the controlled alternating current supply to provide a control of alternating current supply to the measuring resistor as a means of automatically maintaining direct current bridge balance, and a pseudo bridge for potentiometrically measuring the ratio between alternating current in said measuring resistance arm and alternating current in said reference resistance arm, said 10 15 20 pseudo bridge including said standard resistors.
